United States Patent Office.

W. S. SALISBURY, OF ADAMS CENTRE, NEW YORK.

Letters Patent No. 65,283, dated May 28, 1867.

IMPROVEMENT IN DEVICE FOR SUSPENDING HAY-FORKS.

The Schedule referred to in these Letters Patent and making part of the same.

TO ALL WHOM IT MAY CONCERN:

Be it known that I, W. S. SALISBURY, of Adams Centre, in the county of Jefferson, and State of New York, have invented a new and improved Device for Hanging Hay-Forks, etc.; and I do hereby declare that the following is a full, clear, and exact description thereof, which will enable those skilled in the art to make and use the same, reference being had to the accompanying drawings, forming part of this specification.

The present invention relates to a device for hanging or suspending hay-forks, etc., which device is so constructed as to be self-locking, while, at the same time, it is free to swing. In the accompanying plate of drawings my improved device for suspending hay-forks, etc., is illustrated—

Figure 1 being a front view of the same, and

Figure 2 an edge view.

A A, in the drawings, represent the two arms or jaws of the device embraced in the present invention, which jaws are made of a curve shape from end to end, and are pivoted or hinged together at B, so as to swing the one upon the other. C, a ratchet on one section or arm A at the point where hinged together, and D a spring-dog or pawl, secured to the other arm in position to engage with the ratchet C. E E, points hung in outer ends of arms A, so as to revolve therein, these points projecting or extending toward each other.

In using the device above described, the dog or pawl D is first released from the ratchet, when, opening the arm to the proper width for the ends containing the revolving points to embrace the width of the beam, as shown in fig. 1, which it is to span, the points are then driven into the same as far as possible, where, by the spring-dog or pawl, they are held or secured locked, so that, from and upon the arms, a hay-fork or other device can be hung, the arms being free to swing upon their points E, by which they are secured to the beam.

I claim as new, and desire to secure by Letters Patent—

The two arms A, pivoted together at one end, and provided with points E at the other, in combination with the ratchet and spring-pawl, substantially as and for the purpose described.

W. S. SALISBURY.
